UNITED STATES PATENT OFFICE.

JOHN R. NIKOLAIS, OF BRISTOL, CONNECTICUT, ASSIGNOR TO THE WALLACE BARNES CO., OF BRISTOL, CONNECTICUT, A CORPORATION.

STRIP-METAL-FINISHING MACHINE.

Application filed January 3, 1927. Serial No. 158,618.

This invention relates to an improvement in strip-metal finishing machines of the class generally known as filing machines and which are designed to finish the edges of 5 strip metal, such as clock-springs, and the like.

The object of this invention is to provide an efficient machine of the class described, constructed with particular reference to superior 10 accuracy and sensitiveness of performance in use.

With this object in view, my invention consists in a strip-metal finishing machine characterized by its provision with a plurality 15 of self-aligning file-holders disposed at different angles with respect to the strip of metal and with respect to other holders of like character. By the use of the term "file," I wish to have it understood as including all 20 finishing tools of similar abrasive nature, such as stone, and the like.

In the accompanying drawings:

Fig. 1 is an end view of a strip-metal finishing machine constructed in accordance 25 with my invention;

Fig. 2 is a view thereof in side elevation;

Fig. 3 is a top or plan view thereof;

Fig. 4 is a transverse sectional view, on a larger scale, taken on the line 4—4 of Fig. 3;

Fig. 5 is a broken detail plan view of one 30 of the file-holding units, together with a portion of one of the cross-heads;

Fig. 6 is a detached perspective view of one 35 of the cylindrical tool-holders;

Fig. 7 is a broken plan view of a modified 40 form of tool-holder unit as mounted upon one of the cross-heads;

Fig. 8 is an end view thereof;

Fig. 9 is a view corresponding to Fig. 7 but 45 showing another modified form which the tool-holder unit may assume; and

Fig. 10 is an edge view thereof.

In carrying out my invention, as herein shown, I employ a stationary cross-head 11 50 and a movable cross-head 11^a, each of which is provided with two sleeve-like bearings 12 through which transverse tie-rods 13 pass. These tie-rods just mentioned extend from side to side of the machine and are mounted 55 at their ends in the side-pieces 14 of the machine-frame 15.

The cross-head 11 is held stationary on the tie-rods 13 with capacity for adjustment by means of set-screws 16, while the cross-head 11^a has sliding movement on the said

tie-rods toward and away from the sheet-metal strip 17 for the purpose as will hereinafter appear. To effect this movement, the outer face of the cross-head 11^a is provided with two bosses 18, to each of which is pivoted 60 the inner end of a link 19, the outer end of the said link being pivoted to the bifurcated upper end of an arm 20 secured to a rock-shaft 21, which latter has bearing at its opposite ends in the machine-frame and is 65 provided at one end with a hand-lever 22 by means of which the cross-head 11^a may be moved toward and away from the strip 17. To securely hold the cross-head 11^a against 70 outward displacement, I provide the hand-lever 22 with a pawl 23 co-acting with a tooth-sector 24.

Each of the cross-heads mounts a battery 75 of cylindrical, self-aligning tool-holders 25, each carrying a file 26 or other suitable abrasive tool. Each of the said tool-holders is formed with a flanged head 27 and is mounted for limited rotary movement about an axis which is disposed substantially perpendicular to the path of travel of the sheet-metal strip 17 and substantially parallel with the cutting-face of its file 26, in two arms 28 of a tool-holder head 29 provided with a rod-like shank 30 having bearing in a guide-sleeve 31 and in turn mounted in either one 80 of the two cross-heads and secured in place 85 therein by a set-screw 32. The outer end of the guide-sleeve 31 is formed with a bifurcated head 33, the arms 34 of which loosely embrace the opposite faces of the tool-holder 90 head 29, so as to prevent the latter from rotating with respect thereto. The outer end of the shank 30 of each tool-holder head 95 is formed with a threaded bore 35 for the reception of the threaded inner end of an 100 adjusting-screw 36 provided with a knurled head 37 and encircled by a spring 38 and having bearing at its outer end in a longitudinal plate 39, one of which is mounted 105 upon each of the respective cross-heads by means of Z-shaped brackets 40. The spring 38 bears at its outer end against a centering-washer 41 and at its inner end against a 110 spring-adjusting nut 42 mounted upon the threaded portion of the adjusting-screw 36 aforesaid and exerts a constant effort to move the file 26 against the edge of the strip 17.

The knurled head 37 of the adjusting-screw 36, by its engagement with the outer face of the longitudinal plate 39, serves to limit the 110

inward movement of the tool-holder head 29 under the urge of the spring 38 and hence correspondingly limit the movement of the file 26.

5 It will be noted from the drawings that the tool-holder heads are arranged in groups in which the arms 28 of the tool-carrying heads are arranged at different angles from the corresponding arms in adjacent groups 10 with the result that the files are disposed on opposite sides and at different angles with reference to the edges of the strip 17, which is drawn, by the usual means (not shown), longitudinally through the machine so as 15 to be successively acted upon by the various files or other abrasive tools. This results in virtually rounding off the edges of the strip, though upon very close examination it will be found that the edges of the strip are really 20 formed with a plurality of narrow faces disposed at different angles, but the general effect is one of roundness.

Each tool-holder is secured in place in its respective tool-holder head 29 by a collar 43 encircling its end opposite from the head 27 and is provided with a longitudinal passage 44 for the reception of a file 26 which is held in place therein by means of a set-screw 45 engaging one of its faces and forcing the edges of its opposite face against two corresponding clamping-shoulders 46, as clearly shown in Fig. 6 of the drawings.

The cylindrical tool-holder 25 has capacity for slight rotary movement in the arms 35 28 of its respective tool-holder head 29 in a plane substantially parallel with the path of travel of the sheet-metal strip 17, so that under the pressure of the spring 38, the face of the file carried by it will be automatically 40 maintained in alignment with the edge of the strip, so as to bring the full width of its cutting-surface into effective action. The rotary movement just described, which takes place about an axis substantially perpendicular 45 to the strip 17, is limited by providing the head 27 of each tool-holder with a radially-projecting pin 47 entering a notch 48 formed in the tool-holder head 29.

In the modified form of my invention 50 shown in Figs. 7 and 8, the tool-holder 49 carries an abrasive stone 50 and possesses the characteristic, self-aligning feature of my invention by being pivoted, by means of a pin 51, to a yoke-like head 52 carried at the outer 55 end of a spring-arm 53 secured to one or the other of the cross-heads 11 or 11^a.

In Figs. 9 and 10 of the drawings, I have 60 shown another method of mounting the tool-holder 49 and its yoke-like head 52. In this instance, the head 52 is mounted at the outer end of a pivotal-arm 54 swinging upon a stud 55 in one or the other of the cross-heads 11 or 11^a. To normally urge the tool-holder 49 toward the edge of the strip 17, the arm 54 65 has pivoted to it a short rod 56 bearing at

its outer end in a chambered adjusting-screw 57 and encircled by a spring 58, the tension of which is adjustable by means of the adjusting-screw 57 aforesaid.

70 In each of the several forms of my invention herein shown and described, the tool-holder is characterized by being mounted for oscillation about an axis which is disposed substantially perpendicular to the path of travel of the sheet-metal strip 17 and substantially parallel with the cutting-face of the file 26.

75 From the foregoing it will be seen that as the strip 17 is drawn through the machine and weaves its way between the various differentially-inclined abrasive tools, the full width of the cutting-face of each of the said tools will be automatically maintained in contact with the strip by the respective springs 38, 53 and 58, so that not only is the cutting action 80 very rapid but it is very clean and even, owing to the fact that chattering is avoided.

85 I claim:

1. A strip-metal finishing machine, comprising a plurality of self-aligning tool-holders disposed at different angles with respect to each other and with respect to the edge of the strip metal to be finished; abrasive tools carried by said tool-holders; and means for supporting the said tool-holders with capacity for oscillation independently of each other about an axis which is substantially perpendicular to the path of travel of the strip metal and substantially parallel with the cutting-faces of their respective tools; whereby the full cutting-width of the said tools may be automatically maintained in engagement with the strip metal.

90 2. A strip-metal finishing machine, comprising a plurality of self-aligning tool-holders disposed at different angles with respect to each other and with respect to the edge of the strip metal to be finished; abrasive tools carried by said tool-holders; and spring-pressed means for supporting the said tool-holders with capacity for oscillation independently of each other about an axis which is substantially perpendicular to the path of travel of the strip metal and substantially parallel with the cutting-faces of their respective tools; whereby the full cutting-width of the said tools may be automatically maintained in engagement with the strip metal.

95 3. A strip-metal finishing machine, comprising a plurality of self-aligning tool-holders disposed at different angles with respect to each other and with respect to the edge of the strip metal to be finished; abrasive tools carried by said tool-holders; and individually-adjustable spring-pressed means for supporting the said tool-holders with capacity for oscillation independently of each other about an axis which is substantially perpendicular to the path of travel of the strip metal and substantially parallel with the cutting- 100

faces of their respective tools; whereby the full cutting-width of the said tools is automatically maintained in engagement with the strip metal.

5 4. A strip-metal finishing machine, comprising a plurality of substantially-cylindrical self-aligning tool-holders; abrasive tools mounted in said tool-holders; tool-holder heads for supporting the said tool-holders at different angles with respect to each other and with respect to the strip metal to be finished, and each having a cylindrical bore for the reception of one of the said tool-holders and the axis of which is disposed substantially perpendicular to the path of travel of the strip metal and substantially parallel with the cutting-faces of the respective abrasive tools; whereby each of the said tool-holders and abrasive tools has capacity for oscillation, so that the full cutting-width of each of the said tools may be automatically maintained in engagement with the strip metal.

10 5. A strip-metal finishing machine, comprising a plurality of substantially-cylindrical self-aligning tool-holders, each provided with a longitudinal passage for the reception of an abrasive tool; an abrasive tool mounted in each of the said longitudinal passages; tool-holder heads for supporting the said tool-holders at different angles with respect to each other and with respect to the strip metal to be finished, and each having a cylindrical bore for the reception of one of the said tool-holders and the axis of which is disposed substantially perpendicular to the path of travel of the strip metal and substantially parallel with the respective abrasive tools; whereby each of the said tool-holders and abrasive tools has capacity for oscillation, so that the full cutting-width of each of the said tools may be automatically maintained in engagement with the strip metal.

15 6. A strip-metal finishing machine, comprising a plurality of self-aligning tool-holders; abrasive tools mounted in the said tool-holders; reciprocable tool-holder heads for supporting the said tool-holders at different angles with respect to each other and with capacity for oscillation about an axis which is substantially perpendicular to the path of travel of the strip metal to be finished and substantially parallel with the cutting-face of the respective abrasive tools; a shank formed upon each of the said tool-holder heads; and a guide formed with a bearing for preventing its rotation in the said bearing; whereby the full cutting-width of the said tools may be automatically maintained in engagement with the strip metal.

20 7. A strip-metal finishing machine, comprising a plurality of self-aligning tool-holders; abrasive tools mounted in the said tool-holders; reciprocable tool-holder heads for

supporting the said tool-holders at different angles with respect to each other and with capacity for oscillation about an axis which is substantially perpendicular to the path of travel of the strip metal to be finished and substantially parallel with the cutting-face of the said abrasive tool; a shank formed upon each of the said tool-holder heads; a spring for normally urging each of the said tool-holder heads toward the strip metal; an adjusting-screw for limiting the urge of the said spring; and a guide formed with a bearing for the said shank and provided with means for preventing its rotation in the said bearing; whereby the full cutting-width of the said tools is automatically maintained in engagement with the strip metal.

25 8. A strip-metal finishing machine, comprising a plurality of self-aligning tool-holders; abrasive tools mounted in the said tool-holders; reciprocable tool-holder heads for supporting the said tool-holders at different angles with respect to each other and with capacity for oscillation about an axis which is substantially perpendicular to the path of travel of the strip metal to be finished and substantially parallel with the cutting-face of the said abrasive tool; a shank formed upon each of the said tool-holder heads; and a guide formed with a bearing for the said shank and with a bifurcated head for embracing one of the said tool-holders and preventing its rotation in the said bearing; whereby the full cutting-width of the said tools may be automatically maintained in engagement with the strip metal.

30 9. A strip-metal finishing machine, comprising a plurality of self-aligning tool-holders; abrasive tools mounted in the said tool-holders; reciprocable tool-holder heads for supporting the said tool-holders at different angles with respect to each other and with capacity for oscillation about an axis which is substantially perpendicular to the path of travel of the strip metal to be finished and substantially parallel with the cutting-face of the said abrasive tool; a shank formed upon each of the said tool-holder heads; a threaded bore formed in the said shank; a spring for normally urging each of the said tool-holder heads toward the strip metal; and an adjusting-screw co-acting with the threaded bore of the said shank for limiting the urge of the said spring; whereby the full cutting-width of the said tools is automatically maintained in engagement with the strip metal.

35 10. A strip-metal finishing machine, comprising a plurality of self-aligning tool-holders; abrasive tools mounted in the said tool-holders; reciprocable tool-holder heads for supporting the said tool-holders at different angles with respect to each other and with capacity for oscillation about an axis which is substantially perpendicular to the path of

travel of the strip metal to be finished and substantially parallel with the cutting-face of the said abrasive tool; a shank formed upon each of the said tool-holder heads; a threaded bore formed in the said shank; a spring for normally urging each of the said tool-holder heads toward the strip metal; and an adjusting-screw co-acting with the threaded bore of the said shank for limiting the urge of the said spring; and a guide formed with a bearing for the said shank and provided with means for preventing its rotation in the said bearing; whereby the full cutting-width of the said tools is automatically maintained in engagement with the strip metal.

11. A strip-metal finishing machine, comprising a plurality of self-aligning tool-holders; abrasive tools mounted in the said tool-holders; reciprocable tool-holder heads for supporting the said tool-holders at different angles with respect to each other and with capacity for oscillation about an axis which is substantially perpendicular to the path of travel of the strip metal to be finished and substantially parallel with the cutting-face of the said abrasive tool; a shank formed upon each of the said tool-holder heads; a threaded bore formed in the said shank; an adjusting-screw co-acting with the said threaded bore; a spring encircling the said adjusting-screw for normally urging each of the said tool-holder heads toward the strip metal; and a guide formed with a bearing for

the said shank and provided with means for preventing its rotation in the said bearing; whereby the full cutting-width of the said tools is automatically maintained in engagement with the strip metal.

12. A strip-metal finishing machine, comprising a plurality of self-aligning tool-holders; abrasive tools mounted in the said tool-holders; reciprocable tool-holder heads for supporting the said tool-holders at different angles with respect to each other and with capacity for oscillation about an axis which is substantially perpendicular to the path of travel of the strip metal to be finished and substantially parallel with the cutting-face of the said abrasive tool; a shank formed upon each of the said tool-holder heads; a threaded bore formed in the said shank; an adjusting-screw co-acting with the said threaded bore; a spring encircling the said adjusting-screw for normally urging each of the said tool-holder heads toward the strip metal; a spring adjusting-nut threaded upon said adjusting-screw for regulating the tension of the said spring; and a guide formed with a bearing for the said shank and provided with means for preventing its rotation in the said bearing; whereby the full cutting-width of the said tools is automatically maintained in engagement with the strip metal.

In testimony whereof, I have signed this specification.

JOHN R. NIKOLAIS.
